INVENTOR

Robt. M. Fryer.

UNITED STATES PATENT OFFICE.

ROBERT M. FRYER, OF BROOKLYN, NEW YORK, ASSIGNOR, BY DIRECT AND MESNE ASSIGNMENTS, TO THE CARBON CASKET COMPANY.

COFFIN.

SPECIFICATION forming part of Letters Patent No. 340,038, dated April 13, 1886.

Application filed September 10, 1885. Serial No. 176,695. (No mod. d.)

To all whom it may concern:

Be it known that I, ROBERT M. FRYER, a citizen of the United States, and a resident of the city of Brooklyn, county of Kings and State of New York, have invented a new and useful Improvement in the Construction of Coffins, of which the following is a specification.

This invention consists in providing a coffin or casket with a complete lining of charcoal, in the form of slabs formed of pulverized charcoal with adhesive material, and pressed or molded, or of boards or slabs charred or treated by destructive distillation.

The object of my invention is to provide a coffin or casket with a lining of such charcoal as to preserve the shape of the coffin and prevent collapse after the outside or body shall have decayed or fallen off, and which shall at the same time serve as an absorbent for the noxious gases which arise from a body before burial, so that much of the danger arising from such emissions may be avoided in cases of death from contagious diseases.

In the drawings, Figure 1 represents a cross-section of a coffin provided with this charcoal lining. Fig. 2 is a top view of the same, with the bed removed. Fig. 3 is a cross-section of the top or lid.

In the drawings, B represents the coffin as a whole, which is of the usual form.

A represents a lining of charcoal in the

form of slabs, which are secured to and cover the inner surface of the coffin or casket and its cover. These slabs may be formed by mixing pulverized charcoal with any adhesive substance and then pressing or molding the mass, or by charring boards or slabs by a method which need not be described here, as it forms subject-matter for a separate application which I intend to make for Letters Patent of the United States. These slabs, by whatever method produced, are attached to the body of the coffin or casket by any suitable means—ascement, screws, bolts, or rivets—in such relation to each other as to produce close joints at their meeting edges, as at D, and these joints may be further tightened by gaskets of rubber or other suitable material placed between the same.

What I here claim as my invention, and desire to secure by Letters Patent of the United States, is—

A coffin or casket provided with a lining of charcoal in the form of slabs secured to the inner surface, substantially as described.

In testimony that I claim the foregoing as my invention I have signed my name, in presence of two witnesses, this 8th day of September, 1885.

ROBT. M. FRYER.

Witnesses:

WILLIAM H. CLARKSON,
M. I. MCGUIRE.
